ADJUSTABLE CLOTHING FORM

Bernard Oestricher, Brooklyn, N. Y.

Application April 28, 1937, Serial No. 139,398

4 Claims. (Cl. 223—68)

This invention relates to new and useful improvements in an adjustable clothing form.

The invention has for an object the construction of a coat form which is adapted to be adjusted so as to fit suits and coats of different sizes.

More specifically, the invention contemplates the construction of a coat form which is characterized by a coat form body having a panel section which is pivotally mounted at one edge, and support elements within said body and panel section and associated with means for holding the elements in various adjusted positions for adjusting the panel section relative to the body.

Still further the invention proposes the provision of a socket for a post associated with one of said support elements to support the form.

Another one of the objects of this invention resides in so constructing the support elements that they may be adjusted within the body to support the body and panel section in various positions.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an adjustable coat form constructed according to this invention.

Fig. 2 is a transverse vertical sectional view of Fig. 1.

Fig. 3 is a fragmentary enlarged detailed view of the support elements used in the form and the adjusting means thereof.

Fig. 4 is a sectional view similar to Fig. 2, but illustrating a modification of the invention.

Fig. 5 is a bottom elevational view of the coat form shown in Fig. 4.

Fig. 6 is a similar view to Fig. 2 but illustrating another form of the invention.

The adjustable coat form, according to this invention, comprises a coat form body 10 having a panel section 10^a which is pivotally mounted at one of its edges, namely, the top edge 10^b. Support elements 11 and 12 are arranged within the body 10 and are mounted on the body and panel section. A means is provided for holding these support elements 11 and 12 in various relative positions for adjusting said panel section relative to the body section. This means comprises a bracket 13 fixedly mounted by screws 14 upon the support element 12 and having parallel arm portions 13^a extending over the support element

11. These arm portions are formed with parallel slots 15. Support screws 16 engage through these slots and are mounted upon the support element 11. Each of these support screws is provided with a washer 17 and with a spring 18 coaxially mounted thereon acting between the washer 17 and the bracket portion 13^a for resiliently holding the parts together. 5

A standard 19 is fixedly mounted on the support element 11 and threadedly supports a screw 20 10 upon one end of which there is a large head 21. This head 21 is provided with peripheral serrations 22 by which it may readily be gripped and turned. The head 21 is provided with a hub portion 21^a which engages against a projecting portion 13^a on the support element 13. The head 21 may be turned for extending or retracting the screw 20 and so forcing apart the support elements 11 and 12 or allowing these support elements to move closer together. A socket portion 23 is mounted on the bracket 13 and is adapted to receive a support post, indicated on the drawing by the dot and dash lines 24. This support post is for the purpose of supporting the coat form. The socket 23 is provided with a clamp screw 25 25 by which the socket may be clamped upon the post.

The coat form 10 may be constructed of conventional materials. The panel section 10^a is separate from the other portions of the form body 30 and hingedly connected thereto by a cloth or other flexible hinge strip 26. This hinge strip is attached to the adjacent edges of the form body and the panel section. The support elements 11 and 12 are in the form of a partition and extend transversely across a portion of the form body. The support element 12 is fixedly attached to the panel section 10^a, while the support element 11 is fixedly attached to the form body 10. The dot and dash lines 10^b in Fig. 2 indicate an adjusted 35 position of the coat form which is obtained by turning the head 21. Other positions may also be obtained. Gravity is depended upon to cause the panel section and the form body to move together as permitted by the contacting hub portion 21^a and projection 13^a. 40

In Figs. 4 and 5 a modification of the invention has been disclosed in which an arrangement has been made to adjust the form in a manner slightly different to that just described. According to this form of the invention it is possible to cause the front portion or the back portion of the form body to be extended outwards or inwards. There is a form body 30 which has several panel sections, a front panel section 30^a 45

and a rear panel section 30^b. These sections are pivotally connected with the form body 30 by flexible hinge strips 31 mounted at adjacent edges.

5. Support elements 11' and 12' are adjustably mounted upon the panel sections 30^a and 30^b. The adjustable mounting is accomplished by tongues 32 upon the peripheral edges of the support elements 11' and 12' engaging into corresponding grooves formed upon the inner walls of the sections 30^a and 30^b. Springs 33 are connected between the panel sections 30^a and 30^b for normally urging these sections together.

The support elements 11' and 12' are of truly circular shape, disc shape, and are adapted to be interchanged one with the other merely by rotating the coat form 30 when the sections 11' and 12' are in a common plane. With this arrangement it is possible to so position the parts that the support element 12' is connected with the front panel section 30^a as shown in Figs. 4 and 5. The adjustment means between the elements are identical to the previous means and the parts may be recognized by the same reference numerals. When the adjustment means is operated, the support elements 11' and 12' may be separated relative to each other. Since the support element 11' is mounted on the post 24, when the adjustment is made the panel section 30^a will move outwards as indicated by the dot and dash lines 39.

When the support elements 11' and 12' are in a common plane the form 30 may be turned around 180° while the support elements 11' and 12' remain stationary. Then the support element 12' will be connected with the panel section 30^b, and when it is adjusted relative to the support section 11' the panel section 30^b will be moved while the panel section 30^a remains relatively stationary.

40. In Fig. 6, the flexible hinge strip 26' is attached within the body 10 to the upper portion of the back 10^c and to the lower portion of the back 10^d, at the edge 10^{bb} to permit adjustment of the lower back panel section 10^d of the coat form body, by the screwhead 21 of the adjusting device. In other respects this form of the invention is similar to that disclosed in Fig. 2.

50. While I have illustrated and described the preferred embodiments of my invention, it is to be understood that I do not limit myself to the precise constructions herein disclosed and the right is reserved to all changes and modifications coming within the scope of the invention as defined in the appended claims.

55. Having thus described my invention, what I claim as new, and desire to secure by United States Letters Patent is:

1. An adjustable coat form, comprising a coat form body having panel sections which are pivotally mounted at one of their edges, a socket for a post or the like to support said form, a support element connected with said socket, a second support element, means for holding said support

elements in relatively adjusted positions, and means for adjustably connecting said support elements with said body so that the support element with the socket is selectively connected with one of said panel sections.

5. 2. An adjustable coat form, comprising a coat form body having front and rear panel sections which are pivotally mounted at one of their edges, a socket for a post or the like to support said form, a support element mounted on said socket and rotatively engaging one of said panel sections, a second support element rotatively engaging the other of said panel sections, and means operative between said support elements for adjusting the relative positions of said support elements whereby said coat form body may be rotated on said support elements and said means manually operated to adjust said support elements and so cause either said front panel section or said rear panel section to be extended 10 outwards or inwards.

15. 3. An adjustable coat form, comprising a coat form body having front and rear panel sections which are pivotally mounted at one of their edges, a socket for a post or the like to support 20 said form, a support element mounted on said socket and rotatively engaging one of said panel sections, a second support element rotatively engaging the other of said panel sections, and means operative between said support elements 25 for adjusting the relative positions of said support elements whereby said coat form body may be rotated on said support elements and said means manually operated to adjust said support elements and so cause either said front panel section or said rear panel section to be extended 30 outwards or inwards, said rotative mounting of said support elements, comprising elements on the periphery of said support elements, and complementary elements on the adjacent faces of 35 said front and rear panel faces.

40. 4. An adjustable coat form, comprising a coat form body having front and rear panel sections which are pivotally mounted at one of their edges, a socket for a post or the like to support 45 said form, a support element mounted on said socket and rotatively engaging one of said panel sections, a second support element rotatively engaging the other of said panel sections, and means operative between said support elements for adjusting the relative positions of said support elements whereby said coat form body may be rotated on said support elements and said means manually operated to adjust said support elements and so cause either said front panel section or said rear panel section to be extended 50 outwards or inwards, said rotative mounting of said support elements comprising elements on the periphery of said support elements, and complementary elements on the adjacent faces of 55 said front and rear panel faces, said elements comprising tongues and said complementary elements comprising complementary grooves.

60. BERNARD OESTRICH.
